UNITED STATES PATENT OFFICE

AUGUST STANLEY LISS, OF CHICAGO, ILLINOIS, ASSIGNOR TO WESTERN ELECTRIC COMPANY, INCORPORATED, OF NEW YORK, N. Y., A CORPORATION OF NEW YORK

FEEDING DEVICE

Application filed February 16, 1929. Serial No. 340,446.

This invention relates to feeding devices and more particularly to dial feeding apparatus for punch presses.

In manufacturing parts on a quantity production basis, the parts are assembled or formed on a punch press having a rotatable dial thereon, on which the parts are positioned by an operator. The parts are carried to the punching position of the press, worked upon by the press, and moved around to a position where a second operator removes them from the dial.

An object of this invention is the provision of a simple, safe and efficient dial feeding unit adapted to be readily and quickly secured to a blanking, forming, drilling or other processing machine.

In accordance with one embodiment, the invention contemplates the provision of a unitary attachment which may be readily and quickly secured to the crank shaft of a punch press to transmit motion therefrom, through a train of gears, and a Geneva gear to impart rotative motion intermittently to a dial for feeding parts to the punch and die of the punch press. All of the aforementioned moving parts are enclosed in suitable housings to prevent injury to an operator and are also conveniently arranged to facilitate mounting. There is also provided a pin operable in response to the rotation of the Geneva gear to accurately position and lock the dial in position after the completion of each partial rotation thereof.

Other features and advantages of the invention will become apparent from the following description of one embodiment thereof, reference being had to the accompanying drawings, wherein:

Fig. 1 is a fragmentary front elevational view of a punch press equipped with a feed mechanism embodying the features of this invention;

Fig. 2 is a horizontal sectional view taken on the line 2—2 of Fig. 1 in the direction of the arrows;

Fig. 3 is a fragmentary horizontal sectional view taken on the line 3—3 of Fig. 1 in the direction of the arrows; and

Fig. 4 is a vertical sectional view taken on

the line 4—4 of Fig. 2 in the direction of the arrows.

Referring now to the drawings wherein like reference characters designate the same parts throughout the several views, the numeral 5 (Fig. 1) designates generally a punch press having a base 6, of any suitable type, upon which are mounted a bed 7 and uprights 8—8. The uprights support and guide a reciprocating ram 9 which is operated in the usual manner by a crank 10 formed on a shaft 11, a flywheel 12 secured upon the shaft insuring regularity of operation. A bed plate 13 secured to the bed of the press 7 (Figs. 2 and 4) at 14—14 and having a portion thereof extending beyond the front of the bed 7 has a bushing 15 secured thereto by means of a nut 16. Journalled in the bushing is a hollow tapered spindle 17 which is secured in the bushing by a nut 18 and a lock-nut 19, a suitable washer 20 being positioned between the nut 18 and the end of the bushing.

The upper end of the hollow spindle 17 has a disk 21 secured thereto by means of screws 22—22 and has a headed member 23 positioned therein and keyed thereto by a key 24 which is positioned in a keyway 25 cut in the spindle. A headed sleeve 26 is threaded in the lower end of the hollow spindle and has a bolt 27 passed therethrough which is threaded in the lower end of the headed member 23, thereby securing the headed member in the hollow spindle.

Positioned upon the head of the headed member 23 is a material feeding dial 28 of a type suitable to the material which is to be worked upon, which is secured to the headed member 23 by a round slotted nut 29. The dial may be rotated to bring material thereon under the punch by means of an annular Geneva gear 30 which is secured to the under side of the disk 21 by screws 31—31.

Rotative motion is imparted intermittently to the Geneva gear 30 by a driving roller 32 mounted on a spur gear 33 which is rotatably journalled in the bed plate 13 and which meshes with a small gear 34 also journalled in the bed plate. The gear 34 receives its rotative motion from a gear 35 which is secured

to a collar 36 pinned to a rotatable shaft 38 by a pin 39, bolts 37-37 being provided for securing the gear 35 to the collar 36. The rotatable shaft 38 has a beveled gear 40 secured to its upper end by means of a pin 41 which beveled gear meshes with a second beveled gear 42 pinned to the crank shaft 11 of a punch press. This beveled gear 42 may be attached to the end of the crank shaft by 10 removing therefrom the means for retaining the flywheel in place and securing a hollow member which forms a part of the beveled gear 42 thereon by means of a pin 43.

The lower end of the rotatable shaft 38 is 15 journaled in a bushing 44 positioned in the bed plate 13 and the upper end of the shaft is journaled in a member 45 which has an annular portion 46 which encircles an extension 47 of the beveled gear 42. The beveled 20 gears 40 and 42 are held in mesh by means of a nut 48 threaded on the end of the extension 47 of the beveled gear 42, a suitable washer 49 being positioned between the nut 48 and the portion 46 of the member 45.

25 An irregular shaped housing member 50 covers the gears 33 and 34 and supports a pair of bushings 51 and 52 in which a locking pin 53 is slidably mounted. The locking pin has a collar 54 secured thereto in a depending portion 55 of which a cam roller 56 is mounted for engagement with a cam 57 mounted on and rotatable with the spur gear 33. Positioned about the pin 53 and between the bushing 52 and the collar 54 is a spring 58 which 30 urges the pin to the left (Fig. 4) and at predetermined intervals into engagement with one of a plurality of bushings 59 mounted on the periphery of the disk 21 to secure the dial 28 against rotation.

40 The gear 35 is covered by a member 60 over which a V-shaped bracket 61 is positioned for supporting a sleeve 62 which encloses the shaft 38. At its upper end, the sleeve 62 is secured to the member 45 which also supports members 63 and 64 which house the bevel gears 40 and 42.

45 It is believed that a clear understanding of the features of the invention will be had by referring to the following description of the 50 operation thereof. The bed plate 13 having been secured to the bed of a press, and the gear 42 having been secured to the crank shaft thereof, upon rotation of the crank shaft the gear 42 will drive the gear 40 and a shaft 38 secured thereto and thereby impart motion through the gears 35 and 34 to the gear 33 carrying the Geneva gear driving member 32. Once in each rotation of the 55 gear 33 the driving member 32 will engage one of the slots in the Geneva gear 30 to impart motion to the dial 28. Just prior to the engagement of a slot in the Geneva gear by the driving member 32 the cam 57 will be effective to move the cam roller and the shoulder in which the cam roller is mount-

ed to the right to withdraw the locking pin 53 from a bushing 59 in the disk 21. Just subsequent to the disengagement of the driving member 32 from one of the slots in the annular Geneva gear the cam 57 will be effective to permit the spring 58 to move the pin 53 into one of the bushings 59 in the disk 21 to accurately position a part, not shown, under the punch of the punch press.

70 The operation described hereinbefore will be automatically repeated as long as the crank shaft of the punch press is rotating and will be effective to move successive blanks into position to be operated upon the punch and die of the punch press.

75 What is claimed is:

1. A unitary blank feeding device removably attachable to continuous operation punch presses as a unit comprising a bed plate carrying a rotary blank feeding dial, 80 a Geneva gear mounted on the bed plate for imparting a step by step movement to the dial, a spring pressed locking latch carried by the bed plate to lock the dial rigidly and accurately in position between movements 85 thereof, a cam carried by the Geneva gear to operate the locking latch, and driving means to actuate the Geneva gear.

2. A removable unitary blank feeding device for continuous operation punch presses readily securable to the presses as a unit comprising a bed plate carrying a rotary blank feeding dial having a series of holes in the periphery thereof each provided with a bushing having a tapered aperture, a Geneva gear mounted on the bed plate to advance the dial step by step, a spring pressed rod carried by the bed plate and having a tapered end to contact with the bushings of the dial to hold the same rigidly and accurately in position between advancements thereof, a cam carried by the Geneva gear to withdraw the rod from and release it into the bushings, and driving means to actuate the Geneva gear.

3. In a punch press having a removable bed plate, a unitary feeding device adapted to be removably secured as a unit to the punch press comprising a rotatable blank feeding dial removably mounted in the bed plate, means to advance the dial step by step, means operated by the dial advancing means to lock the dial rigidly and accurately in place between advancements, and driving means to actuate the advancing means.

110 In witness whereof, I hereunto subscribe my name this 30th day of January A. D., 1929.

AUGUST STANLEY LISS.
